Specification for Design.

Patented Jan. 13, 1914.

Application filed October 24, 1913. Serial No. 797,145. Term of patent 7 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handles, of which the following is a specification, reference being had to the accompanying drawing, forming part thereof.

My new, original and ornamental design for a burial-casket handle is shown in the accompanying drawing, in which,

Figure 1 is a front elevation of a burial-

casket handle, showing my new design, one end of the same being omitted. Fig. 2 is an end elevation of the same; and, Fig. 3 is a central vertical cross-section of the upper portion of the plate of the same to illustrate the depression in the same.

I claim:

The ornamental design for a burial-casket handle, as shown.

CHARLES BLESCH.
